UNITED STATES PATENT OFFICE.

ARTHUR HENRY HOLLIDAY LEWIS, OF LONDON, ENGLAND.

SELF-INSTRUCTOR FOR GAMES.

1,410,811.

Specification of Letters Patent. Patented Mar. 28, 1922.

Application filed October 19, 1921. Serial No. 508,727.

To all whom it may concern:

Be it known that I, ARTHUR HENRY HOLLIDAY LEWIS, a subject of the King of Great Britain, residing at 23 Ryder Street, London, S. W. 1, England, have invented certain new and useful Improvements in Self-Instructors for Games, (for which application for Letters Patent was filed in Great Britain on the 14th day of October, 1920, Serial No. 29,064,) of which the following is a specification, reference being made to the accompanying drawings, forming a part thereof.

This invention relates to an apparatus or device for enabling a person to detect and correct his errors or faults in playing games, such a golf, tennis, cricket, billiards or other games in which a club or other implement is employed.

20 In playing such games, the correct position or attitude of the body from the beginning to the end of the playing stroke, the grip of the club or implement, and the position of the limbs during the stroke are all essential to successful playing.

Whilst a player can obtain from books, information as to correct playing and common faults, he cannot readily study his own errors, has to rely on information from another person.

It is the chief object of the present invention to provide a handy, cheap, and efficient device whereby a person, in practising a game, can detect and correct his errors or 35 model his game or play on that of some expert or exponent. In accordance with the present invention, there is provided a mirror or reflector which can be suspended, stood or supported at a convenient distance in

40 front of the player and it is furnished with a holder or the like in which can be displayed pictures, diagrams or photographs shewing the correct positions which the player wishes to study and copy. To facilitate the checking of the player's attitude and

45 actions, the mirror may be furnished with one or more vertical and horizontal lines or the like, similar lines or marks being placed on or in front of the pictures or photographs 50 so that the player can check his actions and attitudes relatively to these lines, with the attitude of the model, or the mirror and the picture holder may be furnished with a series of vertical and horizontal lines arranged 55 checker-wise.

With these objects in view, my invention comprises the construction and arrangement of operating parts herein shewn and described as one embodiment of my invention and then particularly pointed out in the appended claims.

Referring to the accompanying drawing:

Fig. 1 is a front elevation and

Fig. 2 is a side elevation of an embodiment of the present invention.

A is the reflector or mirror and B the holder for the picture or pictures.

In the embodiment of the invention illustrated, the device is arranged to be supported from the ground.

The mirror A is preferably convex and is carried in a light frame a.

A leg or support C is adapted to receive or is appropriately connected to the lower 70 side or edge of the mirror or reflector A. The mirror may fit into a slot or opening in the top of the support C so that the two parts can be assembled or taken apart easily or these two members A and C may be permanently secured together.

The leg or support C may be telescopic so that it takes up a minimum of space when not in use and may be telescopic or adjustable so that when the leg is struck into the 85 ground and the device is in use, the distance of the device from the ground may be adjusted in accordance with the requirements of the user.

The pictures shewing the attitudes or postures upon which the user desires to model his play are arranged in series so that they can be quickly and successively displayed in proper relation to the mirror or to the reflection of the user therein. The holder 95 for the pictures conveniently comprises a frame B formed from a piece of wire bent to the shape shewn. The ends b of the frame are turned inward and pass through lugs a' carried by the frame a of the mirror and to 100 retain the frame in the upright position when the device is in use, the ends of the frame may have shoulders adapted to enter recesses in the lugs and to be retained therein by the spring-like nature of the frame, in 105 a well known manner. When the device is not in use, this holder B by being turned back can rest in the concave back of the mirror making the entire apparatus of small compass for carrying.

For convenience in exposing a number of photographs or pictures in series, there are mounted two rings b' b' at the top of the frame B.

5 As each picture B' is required it is turned over from the rear side of the apparatus to the front (see Fig. 2) so that the user having finished with one detail of the play can readily bring the next picture of the series 10 to view above the mirror.

Although in the example shewn the pictures are arranged above the mirror, they may be equally well arranged along side of it.

To facilitate the user adapting himself 15 readily to the attitude or position of the body or limbs shewn in the picture, a convenient number of indicators or guides may be provided, as above stated, both on the mirror and on the pictures. In the example shewn, 20 there are arranged at top and bottom of the picture holder or on each of the pictures indicators B² B³ and in similar positions on the mirror are placed indicators A' A². These indicators provide a guide for the 25 central line of the body.

Similar indicators may be arranged at the sides of the mirror and of the pictures.

Also when golf, for example, is the game being studied, it has been found useful to 30 arrange a series of lines B⁴ checker-wise on the pictures so that the position of the feet of the model and the club can be studied, similar lines A³ being arranged on the mirror.

35 These indicators can consist of threads or wires stretched across the mirror and the picture or consist of discs marked upon the picture and mirror.

In addition to or in place of these indicators, a series of vertical horizontal or other 40 movable or adjustable guides or indicators may be provided.

For example, a number of fine wires or 45 threads having their ends secured to guides movable along the frame of the mirror may be provided, similar wires or threads being adjustably mounted on the frame of the picture holder. In this latter case the wires and threads may be carried upon a supplemental frame to allow for the pictures being 50 turned over or slipped behind the frame. These adjustable indicators can be moved so that the user can study more minutely any particular position or grip.

55 The device has been shewn adapted to be supported from the ground and the leg support shewn may be replaced by a wire support which can be folded back behind the mirror when not in use.

60 The device when used for the game of billiards for example, may be provided with a support for securing it to a table.

It may also be adapted to be hung on a wall so as to be used in a room as for example, for the studying of physical exercises.

As it is well known that one point should be mastered correctly before trying to execute the entire stroke, the pictures will show say in the game of golf, the grip of the hands, then the attitude of body and limbs 70 and the position of the club, at the initial point of the stroke, then the same at one or two points in the execution of the stroke, and finally the correct positions at the end of the stroke. The player standing in front of 75 the device will see himself in the mirror with the picture giving the correct attitude on a line with his own reflection, and having studied and mastered say the grip, he will change the picture to that showing the position at the beginning of the stroke and so on through the series of pictures.

The pictures may be photographs of actual players, so that the person using the device can accurately copy the various acts and 80 attitudes, the aforesaid guide lines enabling him to study minute details of position and detect and correct his errors.

As the reflection of say a right handed player will appear in the mirror as a left 90 handed player, it is necessary that in preparing the picture or photographs that these are made to agree. This can be accomplished by printing the photographs of a right right handed player from a reversed negative thus making the photograph to appear 95 lefthanded.

What I claim as my invention and desire to secure by Letters Patent is:—

1. In a self-instructor, in combination, a 100 mirror, a picture of a figure having an ideal pose, means for supporting the picture adjacent the mirror and in such relationship thereto that the image of the observer in the mirror is closely adjacent the pictured figure, the observer's image and the pictured figure being simultaneously visible to the observer when standing in front of the mirror, and indicating means on the mirror and picture for aiding the observer in positioning 105 himself so that his image is similar to the figure illustrated in the copy picture.

2. In a self instructor, a reflecting surface having coordinate lines superposed thereon, a copy picture adjacent the reflecting surface, including the representation of a figure having an ideal pose and also having coordinate lines superposed thereon, the copy picture and reflecting surface being visible simultaneously by an observer standing in front 115 of the reflecting surface so that the image of the observer in the mirror may be compared with the figure illustrated in the copy picture with the assistance of the coordinate lines.

3. In a self-instructor, in combination, a 120 circular convex mirror, a picture of a figure having an ideal pose, means associated with the mirror for supporting the picture in such relationship to the mirror that the image 125 130

of the observer in the mirror is closely adjacent the pictured figure, coordinate lines on the mirror and corresponding coordinate lines on the picture whereby an observer 5 standing in front of the mirror and simultaneously perceiving his image and the ideal figure, is enabled to compare his image with said figure.

4. In a self-instructor, in combination, a 10 mirror so curved that the image of an observer stationed in front of the same is of relatively small size, a picture of a figure having an ideal pose, means associated with the mirror for supporting said picture in 15 such relationship to the mirror that the image of the observer in the mirror is closely adjacent the pictured figure, the observer's image and the picture being simultaneously visible to the observer when standing in 20 front of the mirror so that the observer's pose may be compared with the ideal pose.

5. In a self-instructor, in combination, a 25 portable curved mirror, a picture of a figure having an ideal pose, means for supporting the picture adjacent the mirror and in such relationship thereto that the image of the observer in the mirror is closely adjacent the pictured figure, the observer's image and the pictured figure being simultaneously

visible to the observer when standing in 30 front of the mirror, indicating means on the mirror and picture for aiding the observer in positioning himself so that his image is similar to the figure illustrated in the copy picture, and supporting means for 35 the mirror including a leg adapted to have one end inserted into the ground and having a member secured to the other end designed and constructed to be readily attached and detached from the mirror. 40

6. In a self-instructor, in combination, a mirror so curved that the image of an observer stationed in front of the same is of relatively small size, a series of pictures showing figures disposed in ideal poses, common means associated with the mirror for supporting said pictures in such manner that any one of them may be brought into such relationship to the mirror that the image of the observer in the mirror is closely 45 adjacent and parallel to the pictured figure, the other pictures being concealed from view, the observer's image and the picture being simultaneously visible to the observer when standing in front of the mirror so that the 50 observer's pose may be compared with the ideal pose. 55

ARTHUR HENRY HOLLIDAY LEWIS.
